UNITED STATES PATENT OFFICE.

SPENCER G. NEAL, OF LOS ANGELES, CALIFORNIA, ASSIGNOR TO CALIFORNIA VALVE AND AIR BRAKE COMPANY, OF LOS ANGELES, CALIFORNIA, A CORPORATION OF CALIFORNIA.

COMPENSATING VALVE.

1,089,574.

Specification of Letters Patent. Patented Mar. 10, 1914.

Application filed January 30, 1913. Serial No. 745,202.

To all whom it may concern:

Be it known that I, SPENCER G. NEAL, a citizen of the United States, residing in the city of Los Angeles, State of California, 5 have invented a new and useful Compensating Valve, of which the following is a specification.

The compensating valve which forms the subject matter of this invention is adapted 10 to a great variety of uses but is more particularly intended as a means for regulating the supply of air under pressure to air braking systems for railways.

In Patent No. 961310 issued jointly to 15 myself and J. M. Childress, June 14th, 1910, we described an engineer's valve comprising a compensating valve which performs all the functions of the valve to which the present invention pertains, 20 but by a less simple construction. In Patent No. 961320 issued jointly to myself and W. H. Sheasby on the same date, said engineer's valve is shown in a somewhat improved form. In the present application, 25 however, there is a radical reconstruction of the compensating valve, the operating elements thereof embodying a very different idea of means and greatly improving upon the structure shown in the two patents above 30 referred to.

The present invention has for its principal object the provision of a compensating valve that will not fail to maintain a predetermined pressure in the train pipe, such 35 train pipe pressure in present practice being reduced (not maintained) when leaks occur in train pipes or fittings.

This newly invented compensating valve operates in connection with, and readily 40 responds to, the pressure used and maintained in the equalizing reservoir, main reservoir and train pipe. It also is adapted to operate in connection with the engineer's valve of present braking systems with but 45 slight alteration of said valve. Moreover this compensating valve maintains any predetermined pressure in the train pipe, during service, lap and running positions.

The feed valve now in general use is not 50 capable of supplying a sufficient quantity of air under varying pressure to provide either for a moderate or for a heavy service application of the brakes in conjunction

with the triple valves described in hereinbefore mentioned Patent 961320, which 55 uses train pipe pressure solely for all service applications. The feed valve in use at the present time is capable of furnishing air to the train pipe in moderate quantities only, and only during such time as the engineer's valve is in running position. This 60 newly invented compensating valve, compensates for loss of air through train pipe leaks or requirements therefrom during service, lap, and running positions. 65

The invention consists in the various parts, combinations of parts and details of construction, all of which will be definitely pointed out in generic and also in more specific claims. 70

Referring to the accompanying drawings which illustrate the invention: Figure 1 is a diagrammatic view illustrating the application of newly invented compensating valve to a well known air braking system. 75 Fig. 2 is a view, the sectioned part of which illustrates certain changes in a well known engineer's valve to adapt the same to co-operate with the compensating valve, which forms the subject matter of this invention. 80 Fig. 3 is a vertical mid-section of the compensating valve. Fig. 4 is a like mid-section of said compensating valve, the valve operating parts being shown in a different position. Fig. 5 is a plan view of a disk, 85 which is inserted in the well known braking valve to adapt same to co-operate with this compensating valve.

Referring in detail to the drawings: 1 is the compensating valve, (see Fig. 1.) 90 2 the engineer's valve and 3 the main storage reservoir for supplying braking air to the train. 4 is the well known main supply pipe leading from the storage reservoir 3 to the brake valve 2, and 5 is the well 95 known branch of the train pipe leading from the brake valve to the main train pipe 6. Pipe 4 may be provided with the well known cut-off valve 7. The brake valve 2 is connected with the usual equalizing 100 reservoir 9 by means of an equalizing pipe 11. Pipe 5 is provided with valve 8. In order to connect the compensating valve 1 with these well known parts, a supply pipe 12 is run from the reservoir pipe 4 to the 105 compensating valve 1, said pipe 12 being

provided with a cut-off valve 14; and an equalizing reservoir pipe 15 is run from the compensating valve 1 to the equalizing reservoir 9 or to the pipe 11, which is in communication with said equalizing reservoir 9. Said pipe 15 is provided with a cut-off valve 16. Pipe 17 is also added to connect the compensating valve 1 to the main train pipe 6; said pipe 17 preferably being furnished with a cut-off valve 18.

The braking apparatus which has been described relates to the engine only, and it is to this part of the braking apparatus of the train that this invention pertains, but in practical operation the braking action on each car of the train is effected.

Referring now more particularly to Fig. 2, this view shows the well known engineer's brake valve altered somewhat in the sectioned portion to adapt same to coöperate with this compensating valve. 22 is the usual train pipe piston chamber, the piston being removed therefrom and a combined metallic and leather gasket or disk 23 being placed over said chamber to make an air tight seal between the equalizing chamber 24 and said train pipe chamber 22. The reason for inserting said gasket 23 is that the well known piston (not shown) which ordinarily occupies chamber 22 would not make an absolutely air tight closure. The main reservoir supply passage 25, the train pipe supply passage 26, the equalizing discharge valve outlet 27 and the train pipe connection 28 are not altered from the standard equipment except that the valve outlet 27 is sealed by a plug.

Referring now in detail to the construction of the compensating valve, shown in section in Figs. 3 and 4, the casing for said valve preferably comprises a spacing ring 31, an upper cap 32 and a lower cap 33, said caps 32 and 33 being clamped against opposite sides of said ring 31 by means of bolts 34 having nuts 35. The inner peripheral portion of the chamber formed by said ring and caps is provided with two tapered recesses 36 and 37 to provide for the proper operation of the diaphragms 38 and 39, which are respectively placed next to the upper cap 32 and lower cap 33. Between said diaphragm 38 and 39 is placed a hollow spacing device 41 having a threaded upward extension 42, around which the diaphragm 38 extends, the diaphragm supporter or clamping nut 43 being screwed upon said extension to hold said diaphragm 38 in place. The lower diaphragm 39 likewise is fitted around a threaded extension 44 and is held in place by a lower clamping nut 45. From pipe 12, already referred to, the fluid pressure supply enters the hollow spacing device 41 through a passage 46 formed in the ring 31. Said passage 46 leads to an annular chamber 47, which is

connected by ports 48 with a central chamber 49, and from said central chamber 49 an outlet passage 51 leads to the train pipe supply valve 52. Said train pipe supply valve 52 is formed on the upper end of the stem 53, the train pipe release valve 54 being formed on or carried by the lower end of said stem 53. Valve cage 55 is screwed on to an externally threaded boss 56 projecting from the lower side of the spacer 41. Said valve cage 55 is provided with a seat 57 with which the valve 52 coöperates, there being outlet passages 58 beneath said seat to admit the air to a train pipe chamber 59 formed within the lower portion of the cap 33. The release valve 54 carried by the lower end of stem 53 coöperates with the valve seat 61, preferably formed on the upper end of an externally threaded bushing 62, said bushing forming the outlet port or passage 63 within which plays the winged extension 64 of said release valve 54. Above the hollow spacer 41 is an equalizing chamber 65 which communicates through pipe 15, already referred to, with the equalizing reservoir 9. Located centrally in the top plate or cap 32 is an adjusting screw or stop 66, which limits the upward movement of the spacer 41, and operating parts connected with said spacer. Said adjusting screw 66 is preferably secured in the adjusted position by a lock nut 67. The train pipe chamber 59 of the compensating valve is connected by a pipe 17 with the main train pipe 6.

Referring to Fig. 5, the disk 23 shown in Figs. 2 and 5 is provided with an aperture 25^a registering with the supply passage 25 and with an aperture 26^a to register with the train pipe supply passage 26. The disk 23 is also provided with the well known equalizing passage 68. Said openings 25^a, 26^a and 68, through the disk 23, furnish outlets to all the passages of the well known engineer's brake valve, the piston chamber 24 alone being closed at its upper end and thereby separated from the chamber 24.

Operation: Before describing the operation it should be remembered that this compensating valve performs all the functions of the equalizing discharge valve and its piston (said piston being dispensed with and removed from the piston chamber 22 of the engineer's valve, as already stated) and in addition to such functions this compensating valve performs certain other functions which will hereinafter be described. The engineer's valve proper will perform all of its well known functions and maintain its various positions as before, viz., full release, running, service, lap and emergency positions.

With the use of the triple valves described in Patents Numbers 961,310 and 961,320 hereinbefore referred to, a gradu-

ated release is obtainable by raising the train pipe pressure to any desired amount, which is accomplished by placing the brake valve in either running or full release position. The only effective difference between these two positions will be a slow or fast graduated release. When the desired reduction of brake cylinder pressure has been obtained, the brake valve will then be moved to lap position, thereby making it possible to retain any desired brake cylinder pressure. Such a raising of the pressure causes the triple valve of the above mentioned patents to effect a graduated release of the brake cylinder pressure; or in other words, partially releasing the air pressure from the brake cylinders in proportion to the increase of train pipe pressure. Either of these positions would be a graduated release. The full release position would cause a quick graduated release and the running position a slow graduated release. Therefore with the use of said patented triple valves these positions would have to be designated as slow and fast graduated release positions.

The charging of the train pipe is caused, as is well known in present braking systems of the standard type, by placing the engineer's valve in the full release position in order to quickly charge the train pipe, said engineer's valve being placed at the running position, as in present practice, as soon as the desired maximum train pipe pressure has been obtained. The train pipe having thus been charged to the required pressure, and the equalizing reservoir 9 also being charged to an equality with the train pipe pressure, the result will be that the pressure in the equalizing chamber 65 which is in communication with the equalizing reservoir 9; will be the same as the train pipe pressure in the train pipe chamber 59 of the compensating valve, said chamber 59 being in direct communication with the train pipe through the pipe 17. With the pressure as just described, in order to make a reduction of the train pipe pressure, the brake valve 2 is placed in the service position, thereby releasing air from the equalizing reservoir 9 to the atmosphere to any desired amount, and thus through pipe 15 releasing the pressure in the equalizing chamber 65 of the compensating valve below the pressure in the lower train pipe chamber 59 of said compensating valve. The result of this change of pressure will be to allow the excess pressure in chamber 59 on the outer side of diaphragm 39 to raise the spacer 41 and parts connected therewith to the position shown in Fig. 3, thus opening the release valve 54 and venting train pipe air through the port 63. When the train pipe pressure in train pipe chamber 59 has thus been reduced beneath the pressure in equalizing chamber 65 said spacer 41 and the

parts directly connected therewith will move back to the lap position, thus closing the relief valve 54 and cutting off further escape of train pipe air.

If instead of reducing the pressure in the equalizing reservoir, as has just been described, the engineer's valve was operated in such a manner as to raise the pressure in the equalizing reservoir 9, and therefore in the equalizing chamber 65 of the compensating valve, the result would be a reverse operation of the compensating valve, the pressure in equalizing chamber 65 exceeding that in train pipe chamber 59 and causing the valve seat 57 to descend from the supply valve 52, thereby opening said valve, as shown in Fig. 4, and supplying air to the train pipe by way of branch pipe 17 which leads from the train pipe chamber 59 of the compensating valve. It is evident that any reduction of pressure in the train pipe chamber 59 will operate the compensating valve in the same manner as an increase of pressure in the equalizing chamber 65. Such reduction may be caused by leaks in the train pipe and also by the operation of the triple valve of Patents 961,310 and 961,320 to supply the desired amount of air to the train pipe for service applications.

The ability of this compensating valve to furnish air pressure to train pipe for all service applications when using the triple valve just referred to eliminates entirely the necessity of the storage system, and also reduces the element of time for recharging of reservoirs in which pressure has been reduced by such service applications.

I claim:

1. A pressure compensating device comprising a casing forming an air chamber, two diaphragms which divide said chamber into three compartments, means to connect said diaphragms together to move in unison, an air pressure supply communicating with the air chamber between said diaphragms, and an air feeding device located in one of the outer chambers, variation of pressure in either of said outer chambers operating said device.

2. A pressure compensating device comprising a casing forming an air chamber, two diaphragms which divide said chamber into three compartments, means to connect said diaphragms together to move in unison, an air pressure supply communicating with the air chamber between said diaphragms, and an air feeding device located in one of the outer chambers, decrease of pressure in the chamber which contains said air feeding device operating said device to feed air to such chamber.

3. In an air brake apparatus, the combination of a main storage reservoir, a train pipe, a pressure-actuated valve to control communication between the train pipe and

the main reservoir, valve-operating means to actuate said valve, said valve being automatically closed by the pressure of train pipe air upon said valve-operating means, and means to admit and release fluid pressure to said valve operating means to control the operation of said valve, said valve-operating means comprising a double diaphragm on the inner sides of which there is the same pressure and from between the parts of which air is supplied to said valve.

4. A pressure compensating device comprising a casing forming an air chamber, two diaphragms which divide said chamber into three compartments, means to connect said diaphragms together to move in unison, an air pressure supply communicating with the air chamber between said diaphragms whereby the same pressure will be on the inner sides of the said diaphragms, an air feeding device operatively connected with said diaphragms, there being an air feeding passage from the air-chamber between said diaphragms to supply air to said air feeding device, and means to vary fluid pressure upon the exterior side of one of said diaphragms to operate said air feeding device.

5. A pressure compensating device comprising a casing forming an air chamber, two diaphragms which divide said chamber into three compartments, means to connect said diaphragms together to move in unison, an air pressure supply communicating with the air chamber between said diaphragms, an air feeding device located in one of the outer chambers and means to vary the pressure in the opposite outer chamber to operate said air feeding device.

40 6. A compensating valve for controlling train pipe pressures and comprising two diaphragms, means rigidly connecting said diaphragms with each other, a fluid pressure supply leading into a passage between said diaphragms, a valve operated by the movement of said diaphragms in one direction to permit air to pass from said passage to the train pipe, and an independently controlled fluid pressure supply to vary the pressure upon one of said diaphragms to actuate the valve.

7. In an air brake apparatus, the combination of a main reservoir, a train pipe, an equalizing reservoir, a brake valve controlling communication between the storage reservoir and the equalizing reservoir and the train pipe, a compensating valve comprising two diaphragms, means rigidly connecting said diaphragms together, means connecting the main reservoir to the space between said diaphragms, means delivering equalizing reservoir pressure against the outer side of one of said diaphragms, means delivering train pipe pressure against the

outer side of the other diaphragm, valves actuated by the movement of the diaphragms and controlling communication between the main reservoir and the train pipe and between the train pipe and the atmosphere.

8. A pressure compensating device comprising a casing containing air chambers, two diaphragms which divide the space within said casing into three chambers, the fluid pressure upon the inner surface of one of said diaphragms always being the same as the fluid pressure upon the inner surface of the other diaphragm, means to connect said diaphragms together to move in unison, an air pressure supply communicating with the air chamber between said diaphragms, an air feeding device operatively connected with said diaphragms, there being an air passage to supply air from the air chamber between said diaphragms to said air feeding device, and means to vary fluid pressure against the exterior side of one of said diaphragms to operate said air feeding device.

9. An air brake apparatus comprising a main reservoir, an equalizing reservoir, a train pipe, a brake valve controlling communication between the said reservoirs and the train pipe, a compensating valve also controlling communication between the main reservoir and the train pipe and between the train pipe and the atmosphere, and means whereby pressure from the equalizing reservoir will control the movement of the compensating valve and place the train pipe in communication with the main reservoir or with the atmosphere in response to variations in the pressures in said equalizing reservoir and the train pipe.

10. A compensating valve for controlling train pipe pressures comprising two diaphragms, means rigidly connecting said diaphragms together and forming a space between them, a fluid pressure supply leading into the space between said diaphragms, valves operated by the movement of the diaphragms in one direction to permit air to pass from between the diaphragms to the train pipe and operated by the movement of the diaphragms in the opposite direction to permit air to pass from the train pipe to atmosphere, and an independently controlled fluid pressure supply acting on the outer side of one of said diaphragms, train pipe pressure acting against the outer side of the other diaphragm.

11. A pressure compensating device comprising a casing forming an air chamber, two diaphragms which divide said chamber into three compartments, means to connect said diaphragms together to move in unison, an air pressure supply communicating with the air chamber between said diaphragms, an air feeding device located in

one of the outer chambers, an air releasing device located in said outer chamber, and means to vary the pressure in the opposite outer chamber to operate said air feeding and air releasing devices.

In testimony whereof I have hereunto signed my name in the presence of two sub-

scribing witnesses at Los Angeles, in the county of Los Angeles and State of California, this 25th day of January, 1913.
